UNITED STATES PATENT OFFICE

LOUIS A. DELAMOTHE, OF OAKLAND, CALIFORNIA

DESIGN FOR AN EAR RING

Application filed March 6, 1931. Serial No. 38,960. Term of patent 3½ years.

To all whom it may concern:

Be it known that I, LOUIS A. DELAMOTHE, a citizen of the United States, residing at Oakland, in the county of Alameda and State of California, have invented a new, original, and ornamental Design for Ear Rings, of which the following is a specification, reference being had to the accompanying drawings, forming part thereof.

Figure 1 is a front elevation of an ear ring, showing my new design;

Figure 2 is a side elevation of an ear ring, showing my new design.

I claim:

The ornamental design for an ear ring as shown.

LOUIS A. DELAMOTHE.
